UNITED STATES PATENT OFFICE.

CHARLES H. LANE AND JOHN H. STEELE, OF PORTLAND, OREGON; SAID LANE
ASSIGNOR OF ONE-SIXTH TO SAID STEELE.

RIVETING DEVICE.

Application filed January 9, 1922. Serial No. 527,992.

To all whom it may concern:—

Be it known that we, CHARLES H. LANE, a citizen of the United States, and JOHN H. STEELE, a subject of the King of Great Britain, both residing at Portland, in the county of Multnomah and State of Oregon, have invented certain new and useful Improvements in a Riveting Device, of which the following is a specification.

10 The present invention relates to a riveting device and has for its principal object to provide means for expanding the end of a rivet in securing one member to a second member the rear side of which is not readily 15 accessible, as for example in securing a name plate to the body of an automobile or like vehicle, the body of which is constructed of sheet metal. Obviously, the invention is adapted for securing any device to sheet 20 metal or any two members together where the rear end is not readily accessible. The present invention is an improvement over our invention disclosed in Letters Patent Number 1,340,778 issued May 18, 1920.

25 A further object of the invention is to provide a device of this nature which will be of extremely simple, durable and inexpensive construction, one which is efficient and reliable in operation, and well adapted to 30 the purpose for which it is designed.

With these and numerous other objects in view, the invention resides in certain novel features of construction, and the combination and arrangement of parts as will be 35 hereinafter fully described and claimed.

In the drawing:—

Figure 1 is an elevation of the tool showing the same in operation,

Figure 2 is a longitudinal section there- 40 through,

Figure 3 is a transverse section there- through taken on the line 3—3 of Figure 1 looking in the direction of the arrow,

Figure 4 is a perspective view of the 45 rivet, and

Figure 5 is a plan view showing the rivet holding a plate to a piece of sheet metal.

Referring to the drawing in detail it will be seen that a sleeve 1 is provided with the 50 longitudinally extending diametrically opposed slots 2 and is internally threaded for the purpose of receiving the bit 3 which is threaded at one end and has the diametri- cally opposed lugs 4 situated intermediate its

ends which are formed preferably by a pin 55 5 passing transversely through the bit. These lugs 4 extend into the slots 2 so as to key the bit 3 to the sleeve 1. The sleeve 1 is provided at one end with the diametri- cally opposed parallelly extending legs 7 for 60 supporting the conical shaped block 8 at their ends. This block 8 is provided with a central bore as is also the adjacent end of the bit 3. A thumb nut 9 is adapted to be threaded on the threaded end of the bit 3 65 whereby the bit may be drawn through the sleeve toward the nut when so desired and for a purpose to be later set forth. A set screw 10 is situated in the drill 3 so as to communicate with the bore thereof for the purpose 70 of holding a wedge pin 11 in the bit as is disclosed to advantage in Figures 1 and 2. This wedge bit 11 is provided with a head 12 at its outer end.

The rivets used in connection with this 75 tool, as shown in Figure 4, are provided with or formed with a disk 13 having a central opening and the right angularly ex- tending semi-cylindrical portions 14 which are normally disposed so as to form a cylin- 80 der. In considering the structure in Figure 1 wherein it is desired to attach the plate 15 to the sheet metal 16, it will be seen that the wedge pin is first inserted into the rivets so that its head 12 will be situated adjacent 85 the ends of the semi-cylindrical portions 14 after which the rivet and pin is passed through the apertures in the plate 15 and sheet metal 16. The other end of the pin 11 is then passed through the bore of the 90 block 8 into the bore of the bit 3 and fixed thereto by the set screw 10. The nut 9 is now rotated so as to draw the bit 3 into or away from the block 8 thereby causing 95 the wedge head 12 to separate the semi-cylindrical portion 14 whereby they will take a position somewhat similar to that disclosed to the left of Figure 1. When the pin 11 has been pulled as far as is possible the same is dis- connected from the bit 3 and may be pushed 100 through the opening in the rivet. Sometimes, of course, it will be necessary to cut the pin adjacent the disk portion of the rivet and in such cases another pin or suit- able instrument may be used for pushing 105 the pin through the rivet out of sight.

Having thus described our invention what we claim as new is:—

A fastener setting apparatus comprising in combination, a pin having a shank portion adapted to pass through a hollow fastener which is to be set and a head portion 5 larger than said hollow fastener adapted to flange the end portion thereof when the pin is pulled in, and means for engaging the shank portion of said pin for pulling the same in comprising a frame, a bit mounted 10 for movement on said frame, means on said

bit for engaging the shank portion of said pin, and means on said frame for moving said bit.

In testimony whereof we affix our signatures in presence of two witnesses.

CHARLES H. LANE.
JOHN H. STEELE.
